UNITED STATES PATENT OFFICE.

LEWIS C. VAN NEST, OF PLAINFIELD, NEW JERSEY.

LOUNGE AND SOFA.

SPECIFICATION forming part of Letters Patent No. 291,244, dated January 1, 1884.

Application filed February 24, 1883. (No model.)

To all whom it may concern:

Be it known that I, LEWIS C. VAN NEST, of Plainfield, in the county of Union and State of New Jersey, have invented an Improvement in Lounges and Sofas, of which the following is a specification.

Lounges have been made with a reversible back secured to the arm and body, respectively, and capable of being turned over in a manner somewhat similar to a railway-car seat. In this case the two edges of the back had to be similar in shape, and the back was only supported by the links that connected it to the body and arm. Lounges have also been made with reversible backs connected by links, but the link at the arm portion extended to the base, and, occupying a diagonal position, was large and objectionable in appearance. The backs of lounges have also been reversible, and secured by bolts or movable transverse bars.

My invention consists in the combination, with the arm and seat, in a sofa or lounge, of a movable back, links that connect the back to the body and arm, and a movable support for the lower edge of the back, whereby the back is held in position very firmly, and it may be placed at either one side or the other of the lounge or sofa for accommodating the sofa to the place where it may stand in the room.

In the drawings, Figure 1 is an end view of the sofa. Fig. 2 is a cross-section at the line *x x*, and Fig. 3 is an inverted plan.

The bottom or seat *A* of the sofa or lounge, the arm *B*, and legs *C* are to be of any desired character. Usually they will be provided with springs and upholstery. The back *D* is of the ordinary or desired shape, and it is to be finished or upholstered on both sides. At the arm *B* there is a link, *e*, that is pivoted at one end to the edge of the back *D*, and at the other end to arm at the middle of its width. The other link, *f*, is pivoted at one end to the edge of the back *D*, and at the other end to the edge of the bottom part, *A*, in the middle of its width. The back can be lifted bodily and moved over from one side of the sofa or lounge to the

other, and in so doing the outer ends of the links *e f* describe semicircles. 50

It is necessary to support the weight of the back, so that it may not be dependent alone upon the links *e f*, and for this purpose I make use of slides *l l*, that pass transversely across below the bottom of the sofa and are held in 55 the loops or supports *m* upon the frame, so that these slides may be drawn out either side of the sofa beneath the back, and said back be supported by the slides. At the ends of the slides there are movable sections of the 60 sofa-frame at each side of the sofa, at seen at *o o'*, and when the slides are moved so as to draw out the section *o'* beneath the back the section *o* is drawn back into the frame-work or base, and when the section *o* is drawn beneath the back the other section, *o'*, will be moved back into the frame. By providing 65 dowels *p* upon the lower edge of the back and holes in the upper edge of the sections *o o'*, the back will be connected to the section by the 70 dowels entering the holes, and this will render the back firm, and also hold the sections and slides in the places to which they may be moved.

The link *e* at the arm *B*, or the link *f* at 75 the bottom *A*, or both, may be slotted longitudinally, so as to allow the back to be set up closely against the side of the lounge and held firmly by tightening up the pivot screw or screws. By loosening these pivot screws the slots in the links will allow the back to be drawn away from the side before lifting the same in reversing the position of such back.

The sections *o o'* may be narrow, and pull 80 out from a long mortise like a drawer-front, instead of extending down to the bottom edge of the frame.

I claim as my invention—

1. The combination, with the sofa or lounge, 90 of a movable back upholstered or finished on both sides, the link *e*, pivoted at one end to the upper part of the arm in the middle of its width and at the other end to the back, the link *f*, pivoted at one end to the bottom part, 95 *A*, of the lounge and at the other end to the

back, the slides *l*, passing across the bottom part of the sofa, and the sections *o o'* upon the ends of such slides and forming supports for the back of the lounge, substantially as set forth.

2. The combination, with the sofa or lounge bottom and arm, of a reversible back, links for the ends of the same, transverse slides, and

sections *o o'* on the ends of the same, substantially as set forth.

Signed by me this 15th day of February, A. D. 1883.

LEWIS C. VAN NEST.
